UNITED STATES PATENT OFFICE.

FRANK R. FISHER, OF ST. LOUIS, MISSOURI.

CRATE-FASTENER.

SPECIFICATION forming part of Letters Patent No. 373,730, dated November 22, 1887.

Application filed August 25, 1887. Serial No. 247,859. (No model.)

To all whom it may concern:

Be it known that I, FRANK R. FISHER, of the city of St. Louis, in the State of Missouri, have invented a certain new and useful Improvement in Crate-Fasteners, of which the following is a full, clear, and exact description, reference being had to the accompanying drawings, forming part of this specification, and in which—

10 Figure I is a perspective view of a crate, showing my improved fastener. Fig. II is an enlarged detail section showing the manner of attaching the springs to the crate. Fig. III is an enlarged detail section taken on line III 15 III, Fig. II. Fig. IV is an enlarged detail section through the top cross-bar in the center of the crate, taken on line IV IV, Fig. I.

My invention relates to a fastening for poultry or other crates; and my invention consists 20 in features of novelty, hereinafter fully described, and pointed out in the claims.

Referring to the drawings, 1 represents the body of the crate, and 2 a movable slat. The slat has openings 3 4 near its respective 25 ends. The top cross-bars of the crate have portions cut away at 5, through which the slat 2 may slide.

6 is a metal strap placed over the reduced portion 5 in the center cross-bar, underneath 30 which the slat 2 may slide, and which prevents the slat from moving upward.

7 are metal springs attached to two of the top slats, 12 and 12 $\frac{1}{2}$, of the crate by means of bolts 8. The slat 12 has circular portions 35 cut on its under side at 9, which permit the springs 7 to bend upward.

10 represents portions of the springs 7, which are bent at right angles to the body of the springs, and which fit in the openings 3 4 in

the movable slat 2 and prevent the slat from 40 sliding either way while they remain in the openings. The opening 4 is made somewhat longer than the opening 3, so that when the spring is raised out of the opening 3 the slat will be permitted to slide far enough to permit the spring at that end to rest on top of the slat before having to lift the other spring up, as it would not be convenient for one person to raise both springs and remove the slat at the same time. 50

11 represents re-enforcing strips, which are secured to the top cross-bars beneath the reduced portions.

Straps similar to that at 6 may be secured to the top end cleats over the slide, as shown 55 by dotted lines, Fig. I.

I claim as my invention—

1. The combination of the body of a crate provided with mortises, a movable slat having openings and adapted to be slid into said mortises, and springs having hook portions to engage in the openings, substantially as and for the purpose set forth. 60

2. The combination of the body of a crate, spring-hooks at each end of said crate, and a 65 movable slat having an opening at each end of different lengths, substantially as set forth.

3. The combination of the body of the crate 1, a slat having openings 3 4, springs 7, and slat 12, having circular portions 9, substantially as 70 described, and for the purpose set forth.

In testimony whereof I affix my signature in presence of two witnesses.

FRANK R. FISHER.

In presence of—

JAS. E. KNIGHT,
EDW. S. KNIGHT.
